UNITED STATES PATENT OFFICE.

RAYMOND S. HUMBURGH, OF ROCHESTER, NEW YORK.

CAR-ROOF CONSTRUCTION FOR REFRIGERATOR CARS.

Application filed June 3, 1924. Serial No. 717,648.

To all whom it may concern:

Be it known that I, RAYMOND S. HUMBURGH, citizen of the United States, residing at Rochester, in the county of Monroe and State of New York, have invented certain new and useful Improvements in Car-Roof Constructions for Refrigerator Cars, of which the following is a specification.

One object of this invention is to provide a new and improved type of car roof construction for refrigerator cars having a double insulating air space with an insulating partition separating the double air space.

Another object of this invention is to so construct the car roof that the insulating partition comprising several layers of strips of felt can be laid in continuous layers over the full length of the car roof.

These and other objects of this invention will be fully illustrated in the drawings, described in the specification and pointed out in the claims at the end thereof.

In the accompanying drawings:

Figure 1 is a vertical sectional view of one-half of a refrigerator car roof showing the improved construction thereof.

Figure 2 is a vertical sectional view of the roof, the section being taken on the line 30 2*-2* of Figure 1.

Figure 3 is a detail perspective view of the pressed steel beam forming part of the upper carlin.

Figure 4 is a detail perspective view of 35 the pressed steel beam forming part of the carlin.

Figure 5 is a detail perspective view and section of a portion of a refrigerator car roof showing the improved construction 40 thereof.

Figure 6 is a vertical section showing a modified form of carlin comprising a metal plate and a nailing strip exposed on the top and bottom for nailing and a sub-carlin 45 comprising an angle iron and a nailing strip exposed on the top and bottom.

In the several figures of the drawings like reference numerals indicate like parts.

The present practice in building refrigerator car roofs is to provide a single air space between the ceiling and the roof of the car with suitable carlins dividing the air space into transverse compartments each having a separate layer or layers of insulating material fastened to the bottom of each of these transverse compartments.

This necessitates the laying of many separate layers of insulating material due to the many compartments into which the air space between the ceiling and the roof is divided up by the transversely extending carlins.

In the car roof construction forming the subject matter of my present invention continuous layers of insulating material extending the full length of the car roof are used and this is made possible by dividing the single air space heretofore provided between the ceiling and the roof into two separate super-imposed air spaces with the layers of insulating material located between two air spaces. The single carlin heretofore used is therefore replaced by an upper carlin 1 and a sub-carlin 2. The upper carlin 1 comprises the U shaped pressed steel beam. The sides of this beam incline toward the middle of the beam where a small portion of the top of the sides of the beam is leveled off so that the upper edge of the inclined sides do not come to a point in the middle of the beam but lead up to a small flat section.

The ends of the sides of the upper carlin are bent outwardly forming a pair of vertical flanges 3 and 4 projecting at right angles from each end of the carlin. The bottom of the carlin is bent upwardly and outwardly at each end of the carlin forming a horizontal flange 5, 5 at each end of the carlin.

The sub-carlin 2 comprises a Z shaped pressed steel beam. The upper edge of the vertical flange of this beam inclines from each end toward the middle of the beam while the lower edge is left straight. To the sides of each of the ends of the Z shaped beam are suitably fastened a pair of flanges 6 and 7 that project at right angles from each side of the vertical flange of the Z beam.

The U shaped pressed steel beam is provided with the wood filler 8 in the form of a wooden beam that rests within the pressed steel beam, being clamped in place therein by means of suitable bolts 9, 9 that pass thru the carlin from one side of the steel beam to the other side thereof. The top of this wooden filler inclines toward its middle being flush with the upper edge of the steel beam at the outer ends thereof and gradually rising above the upper edge of the steel beam until it reaches the middle of the

beam. The incline of the wood filler of the upper carlin corresponds to the pitch of the roof of the car. The middle of the wood filler of the upper carlin is recessed to receive the center beam 10 of the car roof.

The Z shaped pressed steel beam of the sub-carlin 2 has two fillers 11 and 12 clamped thereto, one on each side of the vertical flange of the beam. For this purpose

10 bolts 13, 13 pass thru each filler and the central flange or web of the Z beam to firmly clamp these fillers together and to the sides of the web or flange of the Z beam. The outline of each of the fillers 11 and 12 is 15 the same as that of the Z steel beam itself and in clamping them in place on the Z beam one of the fillers has its bottom exposed and is used for the ceiling nailing strip while the other filler has its top exposed and forms the nailing strip for the insulation supported by the sub-carlin.

In building the car roof according to my invention the sub-carlin 2 is first clamped to the inside of the side plates 14 supported 25 on top of each side of the car. These side plates have the shoulder 15 formed thereon so that the outer end of the sub-carlin can rest thereon. The flanges 6 and 7 of the Z steel beam are placed against the inside of 30 the side plate and suitable bolts 16 pass thru suitable holes provided in these flanges and thru corresponding holes in the side plate and clamp the ends of the sub-carlin rigidly in place against the inside of the side plate 35 to firmly support it thereon. After the sub-carlins are anchored in place between the side plates of the car, the ceiling 17 comprising a series of matched boards is nailed to the bottom of the fillers or nailing strip 40 12 of the sub-carlin.

The ship lap 18 is then nailed to the top of the fillers or insulation nailing strip 11 and on top of this ship lap is placed a series of insulating strips 19, 19. The upper carlins 1 are then placed on top of the insulating strips 19 and anchored in place between the side plates 14 of the car. For this purpose the horizontal flange 5 of each end of the upper carlin is nested into a recess in the 45 top of the side plates while the flanges 3 and 4 are suitably bolted to the inside of the side plates by means of the bolts 20. To the top of the wood filler 8 of the upper carlin are then nailed the roof boards 21, 21 which 50 cover the top of the car from one side plate to the other side plate. As heretofore described the middle of each of wood fillers 8 of the upper carlins are recessed to receive the center beam 10 of the roof connecting 55 all of the upper carlins with one another.

From the foregoing and from an inspection of Figure 5 of the drawing it will be seen that by providing an upper and a sub-carlin and placing a series of continuous 60 layers of insulation which may be made up

of felt strips or other suitable material between the upper and the sub-carlins, two air spaces are created between the ceiling and the roof proper of the car. Furthermore the insulation is formed by continuous 70 strips that extend from one end to the other end of the car forming a continuous and uniform insulating partition between the two air spaces.

I claim:

1. In a car roof construction, the combination of a pair of side plates, an upper and a sub-carlin supported between said side plate with an uniform space between them, an insulating partition placed between said 80 upper and said sub-carlins, a ceiling supported by said subcarlin on the under side thereof and a roof supported on said upper carlin at the top thereof.

2. In a car roof construction, the combination of a pair of side plates, an upper and a sub-carlin supported between said side plates with an uniform space between them, a series of continuous layers of insulating material supported on the top of said sub-carlin, a ceiling supported on the under side of said sub-carlin, a roof supported on the top of said upper carlin.

3. In a car roof construction, the combination of a pair of side plates, an upper and a sub-carlin supported between said side plates with a uniform spacing between them, a rigid partition supported on top of said sub-carlin, a flexible layer of insulating material placed on top of said rigid partition, a ceiling supported on the under side of said sub-carlin and a roof supported on top of said upper carlin.

4. In a car roof construction, the combination of a pair of side plates, an upper and a sub-carlin supported between said side plates independently of each other, an insulating partition separating said sub-carlin and said upper carlin, a ceiling suspended on the under side of said sub-carlin 105 and a roof supported on top of said upper carlin, reinforcing members attached to said upper and said sub-carlins.

5. In a roof construction, the combination of an upper carlin and a sub-carlin said upper carlin comprising a U shaped pressed steel frame, a filler clamped in place in said steel frame and projecting above the top thereof, said sub-carlin comprising Z shaped pressed steel frame having a wood filler 115 clamped to each side thereof and means for supporting said upper and sub-carlin with a space between them.

6. A roof construction comprising an upper carlin and a sub-carlin, both said upper and said sub-carlin comprising a pressed steel frame having wood fillers attached thereto to present nailing strips for attaching a ceiling to said sub-carlin and roofing to said upper carlin and supporting and at- 125 130

taching a continuous layer of insulation to said sub-carlin between it and said upper carlin.

7. A roof construction comprising an upper carline and a sub-carlin, both said upper and said sub-carlin comprising a pressed steel frame having wood fillers attached thereto to present nailing strips for attaching a ceiling to said sub-carlin and roofing to said upper carlin, insulation interposed between the upper carlin and subcarlin and attached to said sub-carlin to space said upper carlin from said sub-carlin a side plate at the ends of said sub-carlin and upper carlin and means for supporting said carlins on said side plates with the insulation between them.

8. In a car roof construction for refrigerator cars the combination of a pair of side plates supported at each side of the car, a sub-carlin comprising a Z shaped pressed steel frame supported between said side plates, nailing strips clamped to each side of said Z shaped steel frame, a ceiling fastened to one of said nailing strips below said Z shaped steel frame, a ship lap fastened to the other of said nailing strips above said Z shaped steel frame, an insulating strip placed above said ship lap, an upper carlin comprising a U shaped pressed steel frame supported between said side plates above said insulating strip, a wood filler forming a nailing strip within said U shaped steel frame and projecting above it, roofing boards nailed on top of said nailing strip projecting from said upper carlin,

9. In a car roof construction, the combination of a metal upper carlin, a wood filler fastened to the metal upper carlin, and forming a nailing strip at the top thereof, roofing attached to said nailing strip, a metal sub-carlin having a pair of wood fillers attached thereto one on each side thereof forming a nailing strip for the top and bottom of said metal sub-carlin, a ceiling attached to the nailing strip formed for the bottom of said metal sub-carlin and a partition attached to the nailing strip formed for the top of said metal sub-carlin, means for independently supporting the ends of said metal upper carlin and said metal sub-carlin at each end thereof.

10. In a car roof construction, the combination of a metal upper carlin, a wood filler fastened to the metal upper carlin, and forming a nailing strip at the top thereof, roofing attached to said nailing strip, a metal sub-carlin having a pair of wood fillers attached thereto one on each side thereof forming nailing strips for the top and bottom of said metal sub-carlin, a ceiling attached to the nailing strip formed for the bottom of said metal sub-carlin and a partition attached to the nailing strip formed for the top of said metal sub-carlin, a continuous layer of insulating material supported on said partition and spacing said upper carlin from said partition.

In testimony whereof I affix my signature.

RAYMOND S. HUMBURCH.
